GARMENT

Vera N. Weiss, University City, Mo.

Application September 10, 1934, Serial No. 743,317

1 Claim. (Cl. 2—224)

This invention relates to garments, and has special reference to a garment designed and adapted to be worn in warm weather with greater comfort than similar garments now in general use.

The invention is embodied in trousers adapted to be worn as pajama trousers or to be worn outdoors at appropriate places, as desired.

An object of the invention is to provide a garment of this character and for this purpose made of light and thin and substantially diaphanous material and having portions thereof rendered opaque by means herein disclosed or other equivalent means, so that the garment may be 15 worn publicly without embarrassment to the wearer.

Other objects of the invention will be apparent from the following description, reference being made to the annexed drawing, in which—

20 Fig. 1 is a perspective view showing the front of the garment.

Fig. 2 is a similar perspective view showing the rear of the garment.

Fig. 3 is a perspective view of the front of the garment turned inside out showing means whereby portions of the garment are rendered opaque.

Fig. 4 is a perspective view showing the rear of the garment turned inside out.

Fig. 5 is a cross sectional view of the body of the garment approximately on the line 5—5 of Fig. 1.

Fig. 6 is a sectional view of the waistband of the garment on the line 6—6 of Fig. 1.

The present invention comprises trousers made of light and thin and substantially diaphanous material, including a body portion 1 and legs 2 extending downwardly from the crotch 3 of the garment. A waistband 4, which is preferably elastic, is attached to the upper end of the garment and has its ends at the front. The garment opens at the front and one end of the waistband has spaced buttons 5 and 6 attached thereto and the opposite end of the waistband has buttonholes 7 formed therein adapted to be engaged with the buttons. Since the buttons 5 and 6 and the buttonholes 7 are spaced substantially in the relationship shown, it is apparent that the garment may be worn with ease and comfort by persons differing considerably in size and may be reduced or enlarged at the waistband by any person wearing the garment.

A section 8, which may be of the same material of which the garment is made or of different material, is attached to the inside of the

crotch of the garment and renders that portion of the garment opaque.

The garment is constructed to open at the front from the waistband to the forepart of the crotch and includes an inner portion 9 and an outer portion 10. The outer portion 10 is designed and intended to overlap the inner portion 9. The outer portion 10 is relatively long and extends laterally relatively a considerable distance. The lower part 11 of the edge of the outer portion 10 extends obliquely upwardly and toward the right from the crotch of the garment to intersection with the upper part 12 of the edge of said outer portion. The edge 12 extends obliquely upwardly and toward the left to connection with the end of the waistband 4. A corner 13 is formed by the intersection of the edges 11 and 12 and a buttonhole 14 is formed through the pointed margin of the outer portion 10 to be engaged with a button 15 attached to the body 1 of the garment a considerable distance from the edge of the inner portion 9.

An approximately diamond shaped section 16 of appropriate material is attached to the inner side of the outer portion 10 of the body of the garment, the outer edges of said section 16 matching and being attached to the margin of the outer portion 10 along the edges 11 and 12 by stitching 17. The lower end of the section 16 extends below the forward end of the section 8 and the parts 8, 9, 10 and 16 are attached together at the lower end of the section 16 and the upper end of the section 8 by stitching 8a. The opposite edges of the section 16 are shaped symmetrically with the edges 11 and 12, including a lower edge portion 18, extending obliquely upwardly toward the left of the garment to intersection at a corner 19 with the upper edge portion 20 that converges upwardly toward the edge portion 12. Stitches 21, running near the edges 18 and 20, pass through the section 16 and the body portion 1 of the garment and secure said parts together. The upper end of the section 16 is attached to the waistband by stitching 22.

A strip 23 of appropriate material is secured to the inside of the inner portion 9 by stitches 24 and constitutes a reinforcement for the fastening means 25, whereby the button 15 is attached to the body of the garment.

In this garment the edges 11 and 18 diverge upwardly approximately along the groins. The two plies 3 and 10 render the portions of the garment covered thereby completely opaque, so that the garment may be worn with comfort and with

45

50

55

out embarrassment wherever it is appropriate to wear such garment.

This garment has been tested and worn with greatly increased comfort during the past extremely hot summer. Therefore, it is known that the garment attains all of its intended objects and purposes efficiently, economically and satisfactorily.

It is possible that the garment may be varied as to details of construction without departure from the nature and principle of the invention as defined by the appended claim.

I claim:

A trousers garment made of diaphanous material and comprising a body portion having a waist band and legs connected with the body portion and forming a crotch, said garment being

open at the front from near said crotch through said waist band, the open front of the garment including inner and outer overlapping portions, said outer overlapping portion being tapered to form a point located substantially midway between the crotch and the waist band and adjacent one side of the body portion, means for attaching said point to the underlying part of said body portion, and a piece of material attached to the inner side of said outer overlapping portion and being shaped to be coextensive with said tapered portion and to extend on the opposite side of the center of the front of the body portion in a like manner and to a similar extent to render the front portion of the garment opaque.
